UNITED STATES PATENT OFFICE.

THOMAS JOHNSON, OF ST. LOUIS, MISSOURI, ASSIGNOR TO JOHNSON & BRANDON, OF SAME PLACE.

DESIGN FOR A VAPOR-STOVE.

SPECIFICATION forming part of Design No. 20,957, dated July 21, 1891.

Application filed April 29, 1891. Serial No. 391,003. Term of patent 7 years.

To all whom it may concern:

Be it known that I, THOMAS JOHNSON, a citizen of the United States, residing at St. Louis, in the State of Missouri, have invented 5 and produced a new and original Design for a Vapor-Stove, of which the following is a specification, reference being had to the accompanying drawing, forming part thereof.

The drawing is a perspective view illustrating my design.

The novelty consists, principally, in the shield A. The shield A extends from the

table T to the shelf S and has rearwardly-extending portions A'. C is ornamental open scroll-work at the rear edge of the shelf S, and 15 which forms a novel feature of the design.

What I claim is—

The design for a vapor-stove, substantially as herein shown and described.

THOS. JOHNSON.
